(57) **CLAIM**

The ornamental design for a bag with asymmetrical seam, as shown and described.

DESCRIPTION

FIG. 1 is a perspective view

FIG. 2 is a front view

FIG. 3 is a back view

FIG. 4 is a top view

FIG. 5 is bottom view

FIG. 6 is a left side view; and,

FIG. 7 is a right side view.

The broken lines showing stitching are for the purposes of illustrating environment and form no part of the claimed design.

Our bag with asymmetrical seam is characterized by the asymmetrical seam across the front and back of the bag.
